PERCUSSION ATTACHMENT FOR PORTABLE DRILLS

Axel E. Lundquist, Unity Township,
Westmoreland County, Pa.

Application July 26, 1954, Serial No. 445,741

3 Claims. (Cl. 255—41)

This invention relates to drills for penetrating rock or masonry work and, in particular, to a device adapted to be used with a portable drill and effective to impart successive impact blows to the shank of a drill as it is rotated continuously.

The object of the invention is to improve generally upon the device of Strobel Patent No. 1,925,289, by providing an attachment which is simpler and cheaper to manufacture, more durable and efficient in operation and capable of drilling a greater depth of hole before replacement of the drill becomes necessary.

In a preferred embodiment of the invention, I employ a driving barrel having a shank adapted to be engaged by the chuck of a conventional portable drill. The barrel is rotatable in one end of a holding sleeve and has endwise engagement with an anvil fixed therein, the contacting surfaces of the barrel and anvil being toothed or notched to produce a continuous series of impact blows on relative rotation. A driven barrel rotatable in the other end of the sleeve has a shank extending rearwardly through the anvil and a chuck or socket on the forward end for receiving the shank of a drill. I provide means to insure rotation of the driven barrel with the driving barrel but permitting relative axial movement therebetween.

A complete understanding of the invention may be obtained from the following detailed description and explanation of the present preferred embodiment illustrated in the accompanying drawings wherein,

Fig. 1 is an axial section through one form of the invention, with parts in elevation;

Fig. 2 is an end elevation;

Fig. 3 is a partial side elevation to enlarged scale showing the notched contacting ends of the driving barrel and anvil;

Fig. 4 is an end elevation of one of said contacting ends;

Fig. 5 is a view similar to Fig. 1 showing a modification;

Fig. 6 is an end elevation thereof;

Figs. 7 and 8 are views of the modified form corresponding to Figs. 3 and 4; and

Fig. 9 is a partial section through a modified form of the chuck in the driven barrel.

Referring now in detail to the drawings and, for the present, to Figs. 1-4, the device of my invention, indicated generally at 10, comprises a driving barrel 11 having a shank 12 adapted to be inserted in the chuck 13 of a portable drill of any conventional type, preferably provided with a built-in driving motor. Barrel 11 has a bore 14 extending into the end thereof opposite shank 12. The barrel 11 is rotatable in one end of a holding sleeve 15 having a handle 16. An anvil 17 in the form of a bored cylindrical block or plug is secured in sleeve 15 by a set screw 18.

A driven barrel 19 rotatable in the other end of sleeve 15 has a shank 20 extending rotatably and slidably through the bore in anvil 17. Barrel 19 has a socket in the end opposite shank 20 for receiving the shank of a

2

rock drill 21 secured therein by a set screw 22. Shank 20 has a flat 23 milled therein. A tapered set screw 24 in a radial tapped hole in barrel 11 has rotary driving engagement with shank 20 but is free from binding contact therewith when turned home, so as to allow relative sliding movement between the shank and barrel 11 limited to the length of the flat but sufficient to permit endwise engagement of the driving barrel and anvil.

The contacting ends of the driving barrel 11 and anvil 17 have teeth or notches 25 and 26, respectively, adapted to interfit, each tooth having an inclined cam portion terminating in a step whereby rotation of the barrel relative to the anvil while their ends are yieldably held in contact by the force exerted on chuck 13 by the user, results in a series of sharp blows being imparted to the anvil. These blows are transmitted directly to driven barrel 19 and drill 21 since the normal forward pressure on handle 16 forces the anvil against the driven barrel. Drill 21 is thus caused to exert a highly effective drilling action by a combination of rotation and percussion.

The attachment is ready for use upon the gripping of shank 12 in chuck 13 and the securing of drill 21 in barrel 19. The portable drill is then held by the usual handle in the user's left hand while the right grips handle 16. When the drill motor is turned on, it drives shank 12 in a clockwise direction looking forward from the motor end to the drill end, the barrel 11 drives shank 20 and the teeth of the barrel ride over those of the anvil 17, causing repeated impact to be applied to the latter by the force exerted by the user's left hand.

Figs. 5-8 show a modification which is similar in all respects to the device already described except for the shape of the teeth or notches 27 and 28 and the details of drill chuck 29 on the driven barrel 30. This chuck includes a frusto-conical portion 31 on the barrel, having a radial hole 32 therein, intersecting the axial socket for the shank of drill 33. A wedging pin 34 is fitted in hole 32. A sleeve 35 having a conical bore 36 is screwed on the outer end of barrel 30 which is threaded to receive it. When the sleeve is turned home, it causes the pin to bind against the shank of the drill, holding it firmly in the socket.

The inner end of sleeve 35 may be grooved as at 37 to form a finger grip and the outer end may be provided with flats 38 to afford a tool hold, to facilitate tightening and releasing the chuck's grip on the drill shank.

The shape of teeth 27 and 28 as shown is such as to impart a light tattoo or vibration to drill 33 as contrasted with the more intensive hammering caused by teeth 25 and 26.

Fig. 9 shows a modified form of barrel 30, designated 39, having a conical socket 40 to accommodate a tapered drill shank 41, and a transverse hole 42 for the usual knockout pin.

It will be apparent from the foregoing that the percussion attachment of my invention is very simple and therefore inexpensive to manufacture. At the same time, it is rugged and durable as well as highly efficient in operation. It materially prolongs the drill life as compared to the results obtained in manual drilling practice, i. e., by hammering the drill and turning it intermittently.

I claim:

1. In a percussion attachment for drills, a stationary holding sleeve having an anvil plug therein, said plug having an axial bore therethrough, means securing the plug against axial movement in the sleeve, a driving barrel extending rotatably into one end of the sleeve, said barrel having a portion adapted to be engaged by a drill, a driven barrel extending rotatably into the other end of said sleeve so as to make endwise contact with said plug, said driven barrel having a shank extending rotatably through the bore of said plug and into said driving

barrel, the adjacent ends of said driving barrel and anvil plug having interfitting sets of teeth, at least one set of teeth having a sloping cam face adapted to contact the other set of teeth whereby, on relative rotation between the driving barrel and anvil plug, the driving barrel is moved axially away from the anvil plug, and means slidably but non-rotatably relating said shank and said driving barrel.

2. An attachment as defined by claim 1 characterized by said means including a recess in said shank and a projection extending from the interior of the driving barrel into said recess.

3. An attachment as defined by claim 2 characterized by said recess being a flat milled in said shank and said projection being a radial screw threaded into the driving barrel.
